UNITED STATES PATENT OFFICE.

GEORGE H. FORSYTH, OF CHICAGO, ILLINOIS.

CAR CONSTRUCTION.

1,081,927.

Specification of Letters Patent. Patented Dec. 16, 1913.

Application filed November 2, 1908. Serial No. 460,654.

To all whom it may concern:

Be it known that I, GEORGE H. FORSYTH, a citizen of the United States, residing at Chicago, in the county of Cook and State of Illinois, have invented certain new and useful Improvements in Car Constructions, of which the following is a specification.

This invention relates to car constructions, and has reference more particularly to that type known as convertible cars, which may be operated as closed cars in cold weather, and converted into open cars having side entrances to the seats thereof in warm weather.

The purposes, objects, and constructional characteristics of the invention will be readily understood from the accompanying drawings and the following detail description; it being stated that several of the individual features of the invention are capable of application to cars generally, whether of the convertible or non-convertible type.

Referring to the drawings—Figure 1 is a vertical transverse section through one side of the car-body and roof. Fig. 2 is an inner side elevation, partly broken away. Figs. 3, 4 and 5 are cross-sectional details, enlarged, on the lines 3—3, 4—4 and 5—5 of Fig. 2, through one of the side posts and the adjacent marginal portion of the closure panels which engage the same. Fig. 6 is a cross-sectional view, enlarged, through one of the side posts on the line 6—6 of Fig. 2. Fig. 7 is an enlarged detail view, illustrating a device for both retracting and locking in any adjusted position the panel closure.

Referring to the drawings, 10 designates the floor, 11 designates as an entirety the vertical side wall, and 12 the roof of a car side. The main posts or uprights of the car side are formed principally of a structural steel beam, herein shown as an I-beam 13, which extends from the floor to the median line of the car roof, being suitably bent to conform to the profile of the side wall, roof and deck of the car, as clearly shown in Fig. 1. These posts lie between the usual window-openings; and, according to the width between these openings, will be used singly or in connected pairs. In both cases, a covering and reinforcement of sheet metal is applied to the beam, as shown at 14, which covering is corrugated on the sides of the posts adjacent to the openings, as shown at 15, in a manner to form guides for the

panel closures, as hereinafter more particularly described, and preferably extends only up to the top of the vertical side portion of the post, although it might be extended wholly or partially to the median line of the car roof. Where the wall portion between adjacent openings employs a pair of such beams, the covering extends entirely around both, as shown in Fig. 6, in which case an internal reinforcement 16 is employed between and secured to the inner adjacent sides of the posts, together with spacing and filling strips 17 between the inner adjacent edges of the flanges of the post. That portion of the covering which is corrugated and lies opposite the edges of the post is also preferably reinforced by internal filling pieces 18. The beams 13 are conveniently secured to the longitudinal side sill of the car by an angularly bent extension 19 of the web secured to the sill as by rivets 20, and further by a bracket 21 riveted at 22 to the web of the beam and at 23 to the sill.

That portion 15 of the covering of the post lying adjacent to the opening between adjacent posts is so corrugated as to form a pair of vertical grooves 24 and 25. Engaging the grooves 24 of a pair of adjacent posts are vertically extending hollow shoes 26 that are formed on their outer sides with beveled or inclined edges 27 engaging correspondingly inclined walls of the grooves 24, whereby said shoes are normally crowded inwardly under a spring action hereinafter described. Between and internally overlapping the inner edges of the shoes 26 is an upper panel closure, which, as shown, comprises a sheet metal sash frame 28 equipped with double glazing 29. The latter are secured tightly in the frame by a pair of triangular-shaped strips 30 and 31, preferably made of bent sheet metal so as to be resilient, said strips being placed with their inclined sides adjacent to each other, and adapted to be drawn together by a bolt 32 so applied as to wedge the strips 30 and 31 together and thus securely hold the margins of the glazing. Bow springs 33 interposed between the vertical sides 28 of the sash frame and the inner transverse walls of the shoe 26 act to force said shoes into snug engagement with the guide-groove 24. Mounted on the inner face of the shoe 26 is a spring-pressed locking plunger 33 (Fig.

2) normally urged into engagement with a socket 34 in the guide. This holds the panel in raised position, and also serves as a convenient aid in removing the panel from the 5 guides, for which purpose the shoe may be thrust inwardly toward the margin of the sash frame against the spring 33 sufficiently to spring the panel out of engagement with its guide. To provide for a limited raising of the upper panel, where it lies just below the lower edge of the roof finish, as shown, the latter may be vertically slotted, as shown at 35, to provide clearance for the knobs 36 of the plungers, so that the latter 10 may engage upper sockets 37 in the guide to hold the sash in raised position.

Engaging each of the V-shaped guide-grooves 25 is a hollow shoe 38 having a wedge-shaped outer edge coöperating with 20 the walls of the guide, said shoe 38 extending from a point substantially opposite the lower margin of the upper panel to the floor of the car. Between the opposed shoes 38 and internally overlapping the inner margins of the parallel walls of said shoes is a 25 frame member consisting of a pair of parallel plates 39, the marginal portions of which are bent at right angles, overlapped, and secured together, as shown at 40 (Figs. 30 4 and 6). The upper portions of the plate 39 are cut away except at their vertical marginal portions, the latter being left to form with the transverse walls 40 channel-shaped 35 guides 41, in and between which is slidably mounted a sash frame 42 carrying a glazing 43 that is secured snugly at its margin by wedge-strips 44 coöperating with an inclined side 45 of the sash frame and secured by bolts 46. The lower portions of the plates 40 40 also have rectangular openings cut therein, and the marginal portions of said openings are turned and bent inwardly toward each other, as shown at 47 (Fig. 6), their 45 transversely disposed meeting edges being united by a strip 48 secured thereto, thereby forming grooves with outwardly inclined side walls adapted to receive the edges of a pair of panel plates 49, the groove-engaging edges of said plates being bent so as to lie 50 parallel with and against the inclined side walls of the groove. The panel plates are secured by a wedge-shaped strip 50, preferably made hollow so as to possess a resilient character, located between and with its inclined sides engaging the margins of the 55 panel plates 49. A bolt 51 passes through the wedge-strip 50 and the transverse wall of the groove, and the wedge-strip is drawn inwardly by nuts 52, access being had there- 60 to with a wrench through an opening 53 formed in the transverse wall of the frame. By reason of this construction not only are the edges of the panel plates 49 securely held in place, but, in tightening up the bolts 65 51, a strong tension is exerted upon the panel

plates, insuring their smooth and level appearance, while they are readily replaceable, when necessary, by simply loosening the wedge-strip 50.

Between the openings occupied by the upper glazing 43 and the lower panel plates 49, the parallel side plates 39 of the frame form a pocket 54 into which the sash frame directly thereabove may be lowered. To lock the sash frame 42 in raised position, I secure 75 to one of the side walls of the channel-guide 41 a bracket arm 55 that extends outwardly through a horizontal slot 56 in the shoe 38 and has mounted therein a spring-pressed plunger 57, the locking end of which passes 80 through a hole in the side of the channel-guide 41 and into a horizontal slot 58 in the frame 42. This supports the latter when the plunger is in locking position, while at the same time permitting edgewise movement 85 of the sash frame 42 relatively to its channel-guide 41; these latter being normally forced apart by an interposed leaf-springs 59.

The vertical sides of the frame formed by the plate 39 are maintained in locked or released position relatively to the shoes 38 by the means shown chiefly in Figs. 5 and 7, these means comprising one or more tensile springs 60 (Fig. 7) that connect the opposed transverse walls of the shoe and frame, tending to draw them together. Applied to these walls are a pair of cam-blocks 61 and 62, respectively, the latter being secured to the wall 40 as by screws 63, while the block 61 has a sliding engagement with the transverse wall of the shoe 38. The proximate inclined faces of the blocks 61 and 62 are each offset laterally so as to provide a pair of smooth engaging faces 63 and 64, while the offset faces are formed, the one with a 105 rack 65, and the other with a smooth surface 66.

67 designates a key having a toothed head 68 that may be entered through an aperture 69, said toothed head lying between the rack 110 65 and the offset surface 66 and, when turned, raising or lowering the cam-block 61, the lowering of the latter locking the panel frame in the shoe and forcing the latter into snug engagement with the grooved 115 guide of the post, and the raising of the block 61 allowing the springs 60 to draw the shoe and panel frame together, and thus allowing the frame and shoe to be readily removed from the guides of the posts. 120

The upper inwardly bent portions of the structural steel beams of the side posts support correspondingly bent outer and inner sheet metal sheathing plates 70 and 71 forming the roof covering of the car, said sheathing being suitably riveted, as indicated at 72, to the flanges of the beams. At points opposite the deck sash opening, the sheathing is cut away, portions of the latter being bent outwardly and inwardly, respectively, to 125 130

form a hood 73 and a deck-sill formation 74 for the deck sash opening indicated at 75.

I claim:

1. In a car, the combination of upright side posts having guides and spaced apart with an opening between them, said opening extending substantially from the floor of the car to the top of the car side, and a panel mounted in said opening and adapted to slide in said guides, said panel being laterally removable from said guides, substantially as described.

2. The combination with a car side having an opening therein, of a pair of telescoping panels detachably mounted in said opening and engaging the vertical margins thereof, said panels being laterally removable from said guides, substantially as described.

3. The combination of a car side having an opening therein with guides along its upright margins, a panel adapted to fit in said opening, one or more movable shoes for said panel coöperating with said guides, and a window mounted on and movable relatively to said panel, withdrawal of one of said shoes from said guides permitting removal of said panel from said opening, substantially as described.

4. The combination of a car side having an opening therein, with guides along its upright margins, of a panel within said opening, and movable shoes between said panel and said guides whereby on withdrawal of one of said shoes from said guides said panel may be removed from said opening.

5. The combination with a car side having an opening extending substantially its full height, of shoes engaging the vertical margins of said opening, and closure members removably mounted at their vertical edges in said shoes.

6. The combination with a car side having an opening extending substantially its full height, of shoes engaging the vertical margins of said opening, closure frames mounted in said shoes, and springs between the edges of said closure frames and said shoes.

7. In a car side, the combination of a structural steel post, a covering for said post corrugated to form a guide, a panel closure, and a shoe coöperating with said closure and adapted to fit in the guide of said covering, substantially as described.

8. In a car side, the combination of a structural steel post, a covering for said post corrugated to form a guide, a panel closure, a shoe coöperating with said closure and adapted to fit in the guide of said covering, and a spring acting on said shoe to maintain the same in said guide, substantially as described.

9. In a car side, the combination of a pair of structural metal posts, coverings for said posts corrugated to form guides, a panel adapted to have its margins fitted in said guides, and means to adjust the width of said panel, substantially as described.

10. In a car side, the combination of a structural metallic post, a covering for said post corrugated to form a guide, a panel closure, a shoe coöperating with said closure and adapted to fit in said guide, and means to retract said shoe toward said closure to permit removal of the latter from the car side, substantially as described.

11. A car side having a series of I-beam posts extending from the floor to the median line of the roof and bent to conform to the profile of the car side, deck and roof, a series of removable panels filling the space between the vertical portions of adjacent posts, and metal sheathing secured to the roof and deck portions of said posts and constituting the exterior and interior roof finish of the car.

12. A car side having a structural metallic post and a sheet-metal covering provided with a corrugation having relatively inclined side faces, substantially as described.

13. A car side having a structural metallic post, a sheet-metal corrugated covering for said post, and a hollow reinforcing member interposed between said post and covering, substantially as described.

14. In a car side, the combination of a structural metallic post, a covering or capping for said post corrugated to form a guide for a panel closure, the side faces of said corrugation being relatively inclined, and a panel closure having at least one surface conforming to a face of said corrugations, substantially as described.

GEORGE H. FORSYTH.
